UNITED STATES PATENT OFFICE

VERTNER DAVID BRITTINGHAM, OF CINCINNATI, OHIO

DESIGN FOR A SPELLING GAME BOARD

Application filed July 13, 1932. Serial No. 44,318. Term of patent 7 years.

To all whom it may concern:

Be it known that I, VERTNER DAVID BRITTINGHAM, a citizen of the United States, residing at Cincinnati, in the county of Hamilton and State of Ohio, have invented a new, original, and ornamental Design for Spelling Gameboards, of which the following is a specification, reference being had to the accompanying drawing, forming part thereof.

The figure is a plan view of a spelling game-board, showing my new design.

The board is approximately one-eighth of an inch thick.

I claim:

The ornamental design for a spelling game board, as shown and described.

VERTNER DAVID BRITTINGHAM.
